ATTORNEY

UNITED STATES PATENT OFFICE.

EZRA B. SMITH, OF RAVENSWOOD, ILLINOIS, ASSIGNOR TO JOHN EDWARD OGDEN, OF MOUNTAINVILLE, NEW YORK.

DOOR.

Application filed December 11, 1922. Serial No. 606,275.

To all whom it may concern:

Be it known that I, EZRA B. SMITH, a citizen of the United States, and a resident of Ravenswood, county of Cook, Chicago, and State of Illinois, have invented certain new and useful Improvements in Doors, of which the following is a specification.

This invention relates to doors and more particularly to doors of the type used as fire doors in elevator hatchways.

One of the objects of the invention is to provide a door having superior fire resisting or insulating properties.

Another object of the invention is to provide a door of the character described that is comparatively light but rigid in construction and that will occupy a minimum amount of space.

Another object of the invention is to provide a door so constructed and arranged that the parts may be readily assembled and secured together.

Another object of the invention is to provide a door having reinforcing means so located as to be concealed thereby not detracting from the appearance of the door.

Another object of the invention is to provide a fire door of minimum weight and maximum strength.

30 Further objects of the invention will appear from the following description taken in connection with the drawings which form a part of this application and in which,

Fig. 1 is a sectional elevation of a portion of an elevator hatchway showing a pair of fire doors mounted therein.

Fig. 2 is a transverse sectional view taken substantially on line 2—2 of Fig. 1.

Fig. 3 is an elevational view, partly broken away, of a fire door constructed in accordance with the invention.

Fig. 4 is an irregular transverse section taken substantially on line 4—4 of Fig. 3, and

Fig. 5 is a sectional elevation taken substantially on line 5—5 of Fig. 3.

The door briefly described comprises a frame which in the embodiment of the invention shown is formed of T-shaped members and corrugated sheet metal sheets secured to the webs of the T-frame. Insulating material such as asbestos or sheet-rock (gypsum) is preferably mounted between the corrugated sheets. The sheets are so rela-

tively disposed that the valleys or depressions and extending portions of one sheet are disposed opposite the respective valleys and extending portions of the other sheet thereby providing air chambers and in the particular form of the invention illustrated these air chambers are vertically disposed. In order to strengthen the door reinforcing members are secured to the top and bottom frame members and are located in the air chambers between the corrugated sheets thereby being concealed from view. Further details of the invention will appear from the following specification.

Referring to Figs. 1 and 2 there is shown an elevator hatchway having vertical guides 10 in which are mounted the fire doors 11 and 12. These doors may be operated in any desired manner and when the upper door 12 is lowered and the lower door is raised they will close the door opening.

In Figs. 3—5 inclusive the details of the door construction are illustrated. The frame of the door consists of four frame members 13 preferably T-shaped in section as shown in Fig. 5 and rigidly secured together at their corners in any desired manner, such as by welding.

The reinforcing members are then secured to the upper and lower door frame members and each of these reinforcing members preferably consists of a tubular member or hollow pipe 14 having a longitudinal slot 15 at each end. As shown in Fig. 5 the slots 15 are made longer than the length of the web 16 of the frame member 13 thereby permitting the tubular members to be mounted in the frame by tilting these members until the webs 16 of the upper and lower frame members are disposed in the slots and then swinging the members 14 to upright position. The members or pipes 14 are then rigidly secured to the webs by riveting or in any other desired manner.

A corrugated sheet 17 preferably having the corrugations extending longitudinally of the door is then secured at one side to the webs 16 of the frame members 13.

If insulating material is to be used this material, such as asbestos sheets 18, is mounted in alignment with the webs 16 of the frame members and thereafters the other corrugated sheet 19 is mounted on the opposite side of the webs 16. The corrugated

2
sheets with insulating material between them are then secured together by rivets 20 as shown in Fig. 4, securing the corrugated members at the depressed portions or valleys 5 21 thereof to the door frame web 16, and thus the insulating material is suitably secured between the sheets.

A slight opening is left between the edges 10 of the corrugated sheets and the door frame 13 to permit for circulation of air and prevent accumulation of dirt within the corrugations.

The frame of the door has secured thereto 15 longitudinally extending webs 22 having offset extensions 23, the webs and extensions 10 being mounted in the vertical guideways 15 of the elevator hatchway and the extensions 23 providing for lateral expansion of 20 the door. The side frame members also have secured thereto lugs 24 to which are attached the operating rods and chains for the door.

Attention is called to the fact that the 25 registration of the valleys and extended portions of the corrugated sheets is particularly advantageous since vertical air chambers are thus produced and the mounting of the reinforcing members or pipes is facilitated and the construction makes it possible 30 to use as many of these reinforcing members as desired without detracting from the appearance of the door since the reinforcing members are concealed from view. The registration of the valleys furthermore permits the use of the same rivets to secure both 35 corrugated sheets to the frame with the insulating material between the sheets.

It will thus be evident that the door constructed and arranged as set forth will 40 possess superior fire resisting or insulating qualities, and will be strong and rigid but comparatively light in construction and may be very economically manufactured. It will also be evident that a door constructed as 45 set forth will not transmit heat. It is a very desirable feature to prevent the temperature within a building from being lowered by the loss of heat through the door.

Although one specific embodiment of the 50 invention has been particularly illustrated and described it will be understood that the invention is capable of modification and that changes in the construction and in the arrangement of the various cooperating parts 55 may be made without departing from the spirit or scope of the invention as expressed in the following claims.

What I claim is:—

1. A door comprising a rigid frame, corrugated metallic sheets secured thereto and a plurality of independent reinforcing members disposed between said sheets and secured to said frame.

2. A door comprising a rigid frame, corrugated metallic sheets secured thereto and

tubular reinforcing means disposed between said sheets and secured to said frame.

3. A door comprising a rigid frame, corrugated metallic sheets secured thereto, said sheets being secured to each other with the valleys in registration and secured together, and a plurality of independent reinforcing members disposed between said sheets and secured to said frame.

4. A door comprising a rigid frame of T-shaped material with the web directed inwardly, corrugated metallic sheets secured to the opposite faces of said web, and reinforcing means disposed between said sheets and secured to said frame.

5. A door comprising a rigid frame of T-shaped material with the web directed inwardly, corrugated metallic sheets secured to the opposite faces of said web and reinforcing means comprising tubular members disposed between said sheets and secured to said frame.

6. A door comprising a rigid frame, corrugated metallic sheets secured thereto with the corrugations disposed vertically, and a plurality of independent reinforcing members disposed between said sheets and secured to said frame.

7. A door comprising a rigid frame of T-shaped material with the webs directed inwardly, corrugated metallic sheets secured to the opposite faces of said web, and tubular reinforcing members secured to the webs of the upper and lower frame members and disposed between said corrugated sheets.

8. A door comprising a rigid frame of T-shaped material with the webs directed inwardly, corrugated metallic sheets secured to the opposite faces of said web, tubular reinforcing members secured to the webs of the upper and lower frame members and disposed between said corrugated sheets, and asbestos material secured between said sheets.

9. A door comprising a frame having an inwardly extending web, sheet metal cover members secured thereto and reinforcing members comprising pipes between said sheets and having longitudinal slots receiving said web and means securing said pipes to said web.

10. A door comprising a rectangular frame having a web extending inwardly from the top, bottom and side members thereof, tubular reinforcing members secured to the web of the top and bottom frame members and corrugated sheets, having vertically extending corrugations, secured to said door frame and covering said reinforcing members.

11. A door comprising a frame and corrugated sheets secured thereto with the corrugations disposed vertically and with the valleys and extended portions of one sheet positioned opposite the valleys and extended

portions of the other sheet and reinforcing means secured to said frame and disposed in the extended portions of the sheets.

12. A door comprising a frame and corrugated sheets secured thereto with the corrugations disposed vertically and with the valleys and extended portions of one sheet positioned opposite the valleys and extended portions of the other sheet, and vertically disposed reinforcing means secured to the top and bottom of the frame and located in the extended portions of the corrugated sheets.

13. A door comprising a rigid frame of T-shaped metallic members with the webs thereof directed inwardly and lying in substantially the same plane, a flat sheet of insulating material between said webs and in the same plane, and corrugated sheet metal sheets over the opposite sides of the sheet of insulating material, affixed to said webs, and means for securing together the covering sheets with the insulating material therebetween.

14. A door comprising a rigid frame of T-shaped metallic members with the webs

thereof directed inwardly and lying in substantially the same plane, a flat sheet of insulating material between said webs and in the same plane, sheets of corrugated metal disposed over the opposite sides of the sheet of insulating material with their valleys in alignment with one another and rivets in said valleys securing the sheets to said frame with insulating material therebetween.

15. A door comprising a rigid frame, a corrugated metallic sheet secured thereto and having valleys and extended portions and tubular reinforcing means secured to the frame and disposed in an extended portion of said sheet.

16. A door comprising an open rectangular frame, a corrugated metallic sheet secured thereto at the top, bottom and sides thereof and having valleys and extended portions and tubular reinforcing means secured to the frame and disposed in an extended portion of said sheet.

In witness whereof, I have hereunto set my hand this 7th day of Dec., 1922.

EZRA B. SMITH.
